(57) CLAIM

The ornamental design for a top surface of a quilt, as shown.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

The single view is a top plan view of a top surface of a quilt, showing my new design.
